[57] CLAIM

The ornamental design for a pet urn, as shown and described.

DESCRIPTION

FIG. 1 is a front elevational view of a pet urn showing my new design;

FIG. 2 is a top plan view thereof;

FIG. 3 is a left side elevational view thereof;

FIG. 4 is a right side elevational view thereof;

FIG. 5 is a rear elevational view thereof; and,

FIG. 6 is a bottom elevational view thereof.

The broken line showing of the dog and the name “Geronimo” in FIGS. 1,3, and 4 is for illustrative purposes only and forms no part of the claimed design.
